A. G. SAART

COMPACT CONTAINER

Filed Jan. 19, 1924

Patented Apr. 7, 1925.

1,532,442

UNITED STATES PATENT OFFICE.

ALBERT G. SAART, OF ATTLEBORO, MASSACHUSETTS, ASSIGNOR TO SAART BROTHERS COMPANY, A CORPORATION OF RHODE ISLAND.

COMPACT CONTAINER.

Application filed January 19, 1924. Serial No. 687,175.

To all whom it may concern:

Be it known that I, ALBERT G. SAART, a citizen of the United States, residing at Attleboro, in the county of Bristol and State 5 of Massachusetts, have invented certain new and useful Improvements in Compact Containers, of which the following is a specification.

My invention relates to containers for 10 toilet accessories such as rouge and powder, and which are also known as vanity boxes.

The essential objects of my invention are to prevent the accidental opening of the rouge closure when the rouge is not in use; to effectively prevent the egress of powder from its compartment when the former is not in use; to facilitate the delivery of powder when desired; to enable the filling of the powder compartment; convenience in 15 operation, and efficiency of the locking means; compactness; and strength. Other objects and advantages will be hereinafter apparent to those skilled in the art.

To the above ends primarily, but not exclusively, my invention consists in such parts and in such combinations of parts as fall within the scope of the appended claims.

In the accompanying drawings which form a part of this specification,

30 Figure 1 is a plan view of a container embodying my invention, in fully extended position,

Figures 2 and 3, sections of the same on lines 2-2 and 3-3 respectively of Figure 1,

35 Figure 4, an enlarged section of the container closed taken on a line corresponding with line 4-4 of Figure 1,

Figure 5, a fragmentary plan view of the hinged mirror member in locked position, 40 and

Figure 6, a fragmentary detail view of a part of the catch or locking means.

Like reference numerals indicate like parts throughout the views.

45 In the embodiment of my invention herein shown the container includes hinged sections 7 and 8 constituting a box body and cover respectively, enclosing a hinged mirror member 9. The box, or bottom member

50 has a base 10 and sides 11. The latter in this instance includes a lining or reinforcing ring or lining strip 12 fast to or integral with the internal portion of the wall and projecting slightly above the same. A

55 bayonet slot 13 in this ring, as shown in

Figure 6, forms an integral resilient tongue 14 which tongue is detached from the external portion of the wall. This resilient tongue has near its free end a rounded projection 15, and, above it, an integral lip 16. 60 The projection extends through a hole 17 in the external portion of the side 11, while the lip 16 is adapted to interengage and lock the section 8.

The box 7 has a substantially circular plate 20 extending transversely of the side or wall 11 intermediate the top and bottom of the latter, and provided with a depending flange 21 frictionally engaging the lining portion 12 of the latter, whose lower edge rests on the base or floor 10. The plate and flange are indented at one point, as at 22, as shown in Figures 1 and 4, to form a space 23 for the movement of the tongue 14. The plate 20 and flange 21 forms a cup which constitutes a closed compartment for loose face powder 26 or the like. At one side of its center the plate is provided with an opening 28 for the introduction of powder. Loosely pivoted upon a rivet or other pivot member 29 in the center of the plate 20 is a disk 32 held in close contact with the top face of the latter by the headed over ends 33 of the rivet 29. The disk has an eccentric opening 34 adapted to register with the opening 28 when the disk is turned to the necessary position. The disk is also provided with a series of perforations 35 arranged together in an area more or less remote from the opening 34, and adapted to 70 register with the opening 28 when the disk is turned. To facilitate turning there is a projection 37 upon the upper face of the disk. 75

The section 8 comprises a top 39 and sides 40. An annular partition plate 41 in this section comprises an annular wall 42, forming a pocket 43, and having one end in contact with the portion 39. Integral with its upper end is an annular horizontal portion 44, from which rises a marginal annular wall 45 forming with the latter a seat 46. The wall 45 terminates in a horizontal portion 47 fast to the side 40. In this case a flange 48 on the portion 47, soldered to the wall 40, serves to hold the plate 41 in place. The pocket 43 is for the accommodation of a rouge plaque or compact 50 against which rests a powder puff or pad 51. 105

The members 7 and 8 are connected by a 110

hinge consisting of a pintle 53 passing through a hinge sleeve 54 formed in the upper portion of the side wall 12 of the box 7, as shown in Figure 4, and completed by 5 hinge sleeves 55 on the wall 40 of the section 8. The wall 40 has near its margin a cavity 57, as shown in Figure 4, adapted to receive the projection 16 which acts as a snap. To disengage the parts the projection 10 15 is manually pushed inwardly.

The mirror member 9 comprises a backing plate 60 having a flange 61 embracing a retaining ring 62 surrounding a mirror 63 and having a flanged over portion 64 for 15 embracing the glass. The member 9 is in this instance hinged by a pin 66 in an angular hinge sleeve 67 on the backing plate 60, and in hinge sleeves 68 on the shouldered portion 47 of the member 41. Thus when 20 the member 9 is closed or folded it rests in the seat 46. For locking it in this position a flat arm 70 is pivoted at one end to a pin 71 fast in the backing 60, and its projecting end slides beneath a flat finger 72 struck up 25 on the portion 47 of the member 41. A hooked elevated projection 73 on the arm 70 serves as a finger piece to move the arm and raise the mirror member.

In full open position the parts assume the 30 positions shown in Figures 1 and 2, with the mirror member supported in operating position by the angular hinge sleeve 67 resting against the partition portion 41. When the member 9 is folded into its seat 46 its 35 back is flush with the face of the partition plate and compactly retains the cosmetic 50 and its puff 51. The latch or arm 70 insures against accidental elevation of the mirror. The location of the plate 20 in an intermediate portion of the section 7 affords a compartment 75 for a powder puff 76 which 40 rests on the disk 32. In use the disk 32 is turned by the projection 37 until the perforations 35 of the disk register with the openings 28 whereupon the section 7 is manually 45 agitated so that the powder arises through the perforations accessible to the powder puff 76. After use, the disk is returned to the

original position shown in Figure 1. To replenish the supply of powder the disk is 50 turned to bring the opening 34 into registration with the opening 28.

It will be understood that while the pivotal connection of the disk 32 with the plate 20 is herein shown as a pivot member, such 55 means for imparting circular motion to the disk is obviously not exclusive, the word pivotally in this application being intended to mean circularly movable.

I claim:—

1. In a container of the type set forth, two hollow cover sections pivotally connected to each other, a mirror member pivotally supported between said sections, a powder-retaining member extended transversely of 65 the one section and having an indentation, and a resilient locking member on the same section movable into said indentation.

2. In a container of the type set forth, two hollow cover sections hinged to each other, a mirror member pivotally supported between said sections, a powder-retaining member extended transversely of the one section and having an indentation, a resilient locking member on the same section 75 movable into said indentation, and means on said member engageable with the first section.

3. In a container of the type set forth, hollow cover sections hinged to each other, a 80 mirror member carried by one section, a powder retaining plate extending transversely of the other section provided with an eccentric opening, a depending flange on the plate embraced by the second section, 85 said plate and flange being provided with a lateral indentation, a resilient locking tongue on the second section movable into the indentation, a lip on the tongue engageable with the first section, and a disk rotatably mounted on the plate provided with perforations adapted to register with the openings.

In testimony whereof I have affixed my signature.

ALBERT G. SAART.
